Primary Examiner — Daniel Bui*Assistant Examiner* — Andrew Kerr(74) *Attorney, Agent, or Firm* — Florek & Endres PLLC(57) **CLAIM**

We claim the ornamental design for a glove, as shown and described.

DESCRIPTION

FIG. 1 is a front and left side perspective view of a glove showing our new invention.

FIG. 2 is a rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line in the figure drawings is included for the purpose of illustrating environment and forms no part of the claimed design.

1 Claim, 8 Drawing Sheets
